UNITED STATES PATENT OFFICE

2,015,654

SEWING MACHINE

Fred Ashworth, Wenham, Mass., assignor to
 United Shoe Machinery Corporation, Paterson,
 N. J., a corporation of New Jersey

Application March 1, 1932, Serial No. 596,051

59 Claims. (Cl. 112—38)

The present invention relates to shoe sewing machines and is herein disposed as embodied in a machine for sewing the welt to the sole and outturned upper of a stitchdown shoe supported 5 on a last.

The thread handling devices of the machine are arranged to form a lockstitch seam and comprise a rotating shuttle located below the work table, a curved hook needle also located below the work 10 table, a loop spreader for moving the needle loop into the path of the shuttle, a curved awl located above the work table, a looper and a thread arm for placing the needle thread in the needle, a rotary take-up for setting the stitch, and a thread lock against which the stitch is set.

For positioning and feeding the work with relation to the thread handling devices, a work support and cooperating presser foot are provided which are arranged to grip and to feed the work in timed relation to the operation of the thread handling devices.

As applied to this machine, a principal feature of the present invention is embodied in mechanism comprising a feed carriage for the work support and presser foot which is rendered operative, upon releasing the foot treadle to stop the machine, to move the work out of the path of the needle in timed relation to and during the continued operation of the stitch forming devices to 25 terminate the stitch forming operation abruptly while the machine is brought more gradually to a stop and to facilitate the removal of the work from the machine.

Another feature of the invention is embodied 30 in novel and improved thread cutting and holding devices arranged to cut both the needle and shuttle threads on one side of the work and to grip the severed ends of the two threads preparatory to the beginning of a new stitching operation.

Another feature of the invention is embodied 35 in a novel and improved presser foot clamping and releasing mechanism which is arranged to clamp the work firmly in position during the stitch forming and working feeding operations, and to release the work during the relative return movements of the presser foot and cooperating work support preparatory to the next feeding movement.

Certain other features of the invention as hereinafter more fully to be described, relate to improvements in the mechanism for threading the needle.

The several features of the present invention consist in the devices, combinations and arrangement of parts hereinafter described and claimed.

which together with the advantages to be obtained thereby will be readily understood by one skilled in the art from the following description taken in connection with the accompanying drawings.

5

In the drawings:

Fig. 1 is a view in side elevation of a lockstitch machine for stitching the welt to the outturned upper and sole of a stitchdown shoe embodying the several features of the present invention; Fig. 2 is an enlarged view partly in section of the two speed starting and stopping clutch shown in Fig. 1; Fig. 3 is a view in front elevation of the head of the machine; Fig. 4 is a view in right side elevation of the head of the machine 15 with the wax pot and thread reel removed to show underlying parts; Fig. 5 is a front view of the machine with the support for the welt severing mechanism broken away and with the parts shown in stopped position; Fig. 6 is a view in 20 right side elevation, partly in section, of a portion of the head of the machine taken substantially on the line 6—6 of Fig. 5 with the feed carriage advanced and the parts in stopped position as in Fig. 5; Fig. 7 is a view partly in section and similar to Fig. 6, but with the feed carriage in its retracted or operating position and the presser foot in clamping position during the 25 operation on a shoe; Fig. 8 is a view in right side elevation of that portion of the machine head 30 shown in Fig. 7 with the wax pot and thread reel removed, the corresponding parts being shown in the same positions as in Fig. 7; Fig. 9 is a view in left side elevation of a portion of the machine head with a portion of the casing broken away 35 to show underlying parts, the feed carriage being shown in its retracted or operating position, and the presser foot in clamping engagement with the work; Fig. 10 is a plan view partly in section of the head of the machine taken on substantially 40 the line 10—10 of Fig. 4, with the parts shown in the positions taken during the movement of the presser foot carriage into inoperative position; Fig. 11 is a detail view of the latch mechanism for controlling the operation of the actuating pin 45 or bolt for the Geneva stop motion with the parts in position just prior to tripping the latch; Fig. 12 is a plan view partly in section, of the head of the machine, taken on substantially the line 12—12 of Fig. 4, with the parts shown in normal operating positions; Fig. 13 is a view in front elevation, partly in section, of a portion of the head of the machine, taken substantially on the line 13—13 of Fig. 4; Fig. 14 is a detail view partly in section of the presser foot mechanism taken sub- 50 55

stantially on the line 14—14 of Fig. 7; Fig. 15 is a detail sectional view of a portion of the presser foot lifting mechanism taken substantially on the line 15—15 of Fig. 8; Fig. 16 is a rear elevation 5 of a portion of the head of the machine, with the back plate removed to illustrate particularly the Geneva stop motion; Figs. 17 to 21 inclusive are details of the mechanism controlled from the starting and stopping pedal to cause the work 10 support and presser foot to be moved into and out of operative position; Fig. 17 being an enlarged view of this mechanism as shown in Fig. 16, but with the parts in position to trip the stop motion, Fig. 18 being a section taken substantially on the line 18—18 of Fig. 17; and Figs. 19, 15 20 and 21 being somewhat diagrammatic detail views of this mechanism illustrating different positions of the safety device for insuring the proper operation of the Geneva stop motion and 25 carrier in timed relation to the starting and stopping of the machine; Fig. 22 is a top plan of the machine with the operating connections for the thread finger, take-up and thread lock shown in dotted lines; Fig. 23 is a detail view showing particularly the thread looper finger; Fig. 24 is an 30 end view of the parts shown in Fig. 23; Fig. 25 is a plan view partly in section of certain of the parts shown in Figs. 23 and 24; Fig. 26 is a front view on a large scale of the take-up mechanism; Fig. 27 is a sectional view of the take-up mechanism taken on the line 27—27 of Fig. 26; Fig. 28 is a view taken on the line 28 of Fig. 27; Fig. 29 35 is a detail view in side elevation of the presser foot and work support carriage; Fig. 30 is a plan view of the carriage shown in Fig. 29; Fig. 31 is an enlarged detail view in front elevation of the shuttle; Fig. 32 is a sectional view on the line 32—32 of Fig. 31; Fig. 33 is a detail view in right side elevation on an enlarged scale, of the welt 40 cutting device; Fig. 34 is a view similar to Fig. 33, with one fork of the knife actuating lever and the toggle release broken away to show underlying parts; Fig. 35 is a plan view of the knife 45 actuating lever and the latch for holding the knife in inoperative position, shown in Figs. 33 and 34; Fig. 36 is a view in front elevation of the welt cutting device with the feeler withdrawn from the work; Fig. 37 is a view similar to Fig. 36 with the feeler depressed into operative engagement with the work; Fig. 38 shows the operation 50 of the cutting device to sever the welt upon engagement of the feeler with the leading end of the welt; Fig. 39 is a detail view partly in section of the feeler member for actuating the welt cutting mechanism and the slide on which it is mounted; Fig. 40 is a sectional view taken on the line 40—40 of Fig. 39; Fig. 41 is a somewhat diagrammatic view in side elevation, illustrating the stitch forming instrumentalities including the looper, 55 needle and awl and their driving connections for one position of the stitch forming devices with the awl through the work; Fig. 42 is a view similar to Fig. 41 showing a different position of the parts, the awl having now been withdrawn and the needle passed through the work; Fig. 43 is a detail view illustrating the manner in which the looper cooperates with the needle to place a 60 loop of needle thread in the needle hook; Fig. 44 is a sectional view taken on the line 44 of Fig. 43; Figs. 45, 46 and 47 inclusive, are views similar to 65 Figs. 41 and 42, showing different positions taken successively by the stitch forming devices to complete the operation of forming a stitch; Figs. 48 to 53 inclusive, are a series of views in front elevation illustrating particularly the operation of 70

the looper and thread finger in the formation of a stitch; Fig. 54 is a detail sectional view taken substantially on the line 54—54 of Fig. 8, illustrating particularly the thread cutting and gripping mechanism just prior to the operation of the knife 5 to sever the threads; Fig. 55 is a view similar to Fig. 54 showing the positions of the parts immediately after the thread gripping and severing devices have operated to cut the threads and grip the loose ends; Fig. 56 is a detail plan view of the 10 needle thread gripper shown in the inoperative position illustrated in Fig. 54; Fig. 57 is a view similar to Fig. 56 with the thread gripper shown in the clamped position shown in Fig. 55; Fig. 58 is a detail plan view of the shuttle thread gripping device as shown in Fig. 55; and Fig. 59 is a detail perspective view on an enlarged scale of the sliding support for the feeler member shown in Figs. 39 and 40.

In the lockstitch shoe sewing machine herein 20 disclosed as embodying in a preferred form the several features of the present invention, the work support and presser foot are mounted on a feed carriage which is movable in the direction of feed to impart the required feeding movements to the work relatively to the thread handling devices including the needle, awl and shuttle which are supported in cooperative relationship on stationary parts of the machine frame. 30

As specifically disclosed in the drawings, the thread handling devices comprise a curved hook needle indicated at 2, an awl 4, a looper 6 for placing the thread in the hook of the needle, a cooperating thread finger 8, a shuttle 10, and a 35 loop spreader 12. The work is held during the stitch forming operation between a work support indicated at 14 and a presser foot 16.

The driving mechanism of the machine includes a horizontally arranged shaft 18 which is 40 continuously rotated by means of an electric motor 20 through a gear 22 secured to the shaft 18, an intermediate gear 24, and a gear 26 on the armature shaft of the motor. Two pulleys 27 are mounted on the shaft 18 to receive a belt so 45 that the machine can be driven alternatively from an outside source of power through a counter drive shaft when so desired. The horizontal shaft 18 is connected to drive a vertical shaft 28, which extends upwardly to the head of the machine, through a starting and stopping clutch 50 which comprises a disk clutch member 30 loosely sleeved on the horizontal shaft 18 and provided with a bevel gear 32 meshing with a corresponding bevel gear 34 on the lower end of the vertical shaft 28. A driving clutch member 36 is formed on one end of a sleeve keyed to turn with the shaft 18 and is slidable lengthwise thereof into and out of driving engagement with the clutch member 30. The driving clutch member 36 is actuated from a starting and stopping treadle 38 to provide a slipping engagement of the members under a relatively light pressure for a slow speed of operation at starting and stopping, and to provide a locking engagement of the members for the normal full speed operation of the machine, through connections including a bell-crank clutch actuating lever 44 and a connecting link 42 as hereinafter more fully to be described. 55

A tension spring 50 connected at one end of the treadle and at its other end to a fixed point on the machine, tends to hold the treadle in raised position with the clutch members out of operating engagement. 70

The stitch forming and work feeding devices of the machine are actuated in timed relation to form a stitch and feed the work during a complete cycle of operations of the machine through 5 connections from the vertical shaft 28 which include a horizontally located cam shaft 52 which is driven from the vertical shaft 28 by the engagement of a worm 54 on the shaft 28 with a worm gear 56 on the cam shaft 52.

10 The needle 2 and awl 4 are supported and actuated in a manner similar to that disclosed in the inventor's Patent No. 1,824,063, dated September 22, 1931, but may be briefly described as follows in connection with Figs. 13, 41, 42, and 45 to 15 47. As best shown in Fig. 13, the needle is mounted on a needle segment 58 secured to a rock shaft 60 journaled in a sleeve 90 mounted in a fixed bearing in the machine. The segment is connected by 20 a link 62 to a lever arm 64, which is also connected by a link 66 to one arm of a lever 68, which at its other end is connected through an arm 70 to a crank pin 72 offset from the axis of the cam shaft 52. The awl 4 is mounted on a segment 74 which is secured to a rock shaft 76 journaled at 25 one end in a fixed bearing of the machine, and at its other end centered in the end of the needle rock shaft 60. The awl is actuated from a crank pin 78 offset from the axis of the cam shaft 52 through connections which include an arm 80 30 formed on the hub of the awl segment 74, a link 82 connecting the arm 80 to a lever arm 84, and a link 86 connecting the crank pin 78 to the lever arm 84.

The needle guide 88 is formed on the sleeve 90 forming the bearing for the needle rock shaft 60, and is actuated in timed relation thereto, as best shown in Figs. 5, 9 and 13, by means of a rack 92 which is slidably mounted in a support 94, and at its lower end engages with a gear segment 40 formed on the sleeve 90, and at its upper end engages with a corresponding gear segment formed on a lever arm 96 secured to a rock shaft 98 which also carries an arm 100 provided with a cam roll 45 engaging in a groove 102 formed in one face of the worm gear 56 on the cam shaft 52.

The shuttle with its actuating mechanism is substantially similar to that disclosed in the patent to Ashworth No. 1,824,063, dated September 22, 1931, but may be briefly described as follows in connection with Figs. 3, 5, 6, 31 and 32 of the drawings. With the present construction, the shuttle 10 which is of the rotary type, is located beneath the work, and comprises a shuttle casing formed of a gear 107 having its center portion cut away to receive the bobbin or cop casing 108, and two flanged plates 109 and 110 which are screwed to opposite faces of the gear and project beyond the ends of the gear teeth to form a track or groove which is engaged by correspondingly shaped supporting and guiding tongues (see Fig. 5) formed on supporting brackets 111 for the shuttle. The shuttle is driven by means of a gear 112 which is arranged to mesh with the gear member 107, and is secured to one end of a drive shaft 114 which carries at its other end a worm gear 116 arranged to engage with the worm gear 56 on the cam shaft 52. The loop of needle thread is taken in the shuttle hook 118, and is held in position between adjacent teeth of the gear 107 as the loop is carried around the shuttle. With the present construction, the cop casing 108 is arranged to permit the rotation of the shuttle relatively thereto, being provided with a flange 119 arranged to fit in a corresponding groove formed between the flanged

plate 110 and the gear 107. A door 120 hinged on the front side of the casing 108 and normally held in closed position by a spring latch 121, provides convenient access by the operator for replenishing the supply of shuttle thread. The casing 108 is held in a stationary position against rotation with the shuttle by means of two spring-pressed arms 122 pivotally mounted on the shuttle supporting brackets 111, and arranged at their upper ends to engage in corresponding slots 123 formed in the casing. In order to permit the loop of needle thread to be passed over the shuttle without interference, these arms are provided with downwardly projecting portions which are arranged to engage with corresponding cams 124 on the under side of a disk 125 secured to the end of the shuttle drive shaft 114, so that each of the arms will be momentarily lifted in turn during the rotation of the shuttle to permit the passage of the needle loop. A spring tension member 126 is mounted on the shuttle casing to tension the shuttle or locking thread as it is led from the bobbin.

The loop spreader 12 is constructed and arranged substantially as in the machine of Patent No. 1,824,063, and comprises an arm secured at its rear end to a rock shaft 128, so that a forward and backward movement is imparted to the notched tip of the loop spreader across the path of the shuttle hook. 30

There is also secured to the rock shaft 128 a short arm provided with a gear segment 130 which engages with a corresponding gear segment formed on one arm of a cam lever 132, which on its other end is provided with a cam roll 35 134 arranged to engage in a cam groove 136 (see Fig. 7) formed in one face of a cam disk 137 on the cam shaft 52.

The thread handling devices of the illustrated machine include a forked looper 6 (see Figs. 5, 40 and 41 to 44) which is arranged to place the needle thread in the hook of the needle substantially at the limit of its upward stroke through the work. The looper is formed on the lower end of a looper arm 137, and comprises a head having a thread eye and a recess at one side of the thread eye forming a fork across which the thread is stretched while being applied to the hook of the needle. The arm of the fork opposite the thread eye is provided with a notch 135 arranged to receive and position the thread when deflected sideways by the thread finger. Inasmuch as the lateral movement of the thread finger takes place at a slight angle rearwardly of the line of feed, it has been found necessary to 50 elongate the rear side of the notch to insure the proper engagement of the thread therewith. The looper arm 137 is mounted for vertical adjustment in a bracket formed on a looper slide 138 which is provided with guiding pins 140 arranged 55 to engage in a slot 142 in a fixed bracket 144. In order to cause the needle thread to be positioned out of the path of the sewing instruments, and more particularly the awl during its advancing movement through the work, the 60 bracket 144 and slide 138 are arranged to impart a movement to the looper towards and away from its thread applying position in a plane which is slightly inclined to the plane of the needle. At its lower end the slot 142 is turned 70 inwardly slightly, so that the looper at the bottom of its down stroke is moved rearwardly to bring the thread firmly into the needle hook. The looper is actuated through connections comprising a cam lever 146 (see Figs. 4, 6 and 22) 75

which is mounted intermediate its length on a pivot 148, and at its rear end carries a cam roll 150 which engages a cam groove in the periphery of a drum 152 mounted on the vertical drive shaft 28. The forward end of the lever 146 is forked to receive blocks 154 forming a socket for a ball at the outer end of an arm 156 projecting from the slide 158.

Cooperating with the looper 6 is a thread finger 10 in the form of a pair of thread engaging members which are arranged to enclose the thread between them and lay it across the forked edge of the looper in position to be taken by the needle hook. The thread finger, as best shown in Figs. 5, and 15 22 to 25 inclusive, comprises a relatively stationary member 8 which has at its lower end an offset thread engaging nib, and its upper end has a horizontally arranged stem which is rigidly clamped to the lower end of a slide 158. Cooperating with the member 8 is a corresponding member 160 provided with an offset nib arranged to engage with the nib on the member 8, and loosely sleeved on the stem portion of the member 8, being normally held in position with the nibs in 25 engaging position by the pressure of a spring 162. The thread finger has a bodily movement in a substantially vertical plane inclined to the plane of the needle and diverging from the plane of movement of the looper. In order to avoid interference with the work, and with other parts of the machine, the thread finger during its lateral and upward movements for positioning the thread across the looper fork, is also carried slightly to the rear of the line of feed. The slide 158 carrying 30 the thread engaging members of the thread finger is mounted for vertical movement in a bracket 164 which is provided with a sleeve hub 166 journaled to turn in a fixed bracket 168 to impart lateral movements to the thread finger across 35 the notched end of the looper. To impart vertical movements to the thread finger, a rack is formed on the slide 158 to engage with the corresponding gear segment on a lever arm 170 which is secured to a rock shaft 172 journaled within the 40 sleeve hub 166 of the bracket 164. At its rear end the rock shaft 172 is provided with an upwardly extending arm 176 which is connected by a link 178 to one arm of a bell-crank cam lever 180 which on its other arm carries a roll 182 arranged to 45 engage in a cam groove on the upper face of the cam drum 152. The bracket 164 is rotated about its pivot to impart lateral movements to the thread finger through connections which include a gear segment formed on a short lever arm 184 on the 50 sleeve hub of the bracket 164 and arranged to mesh with the corresponding gear segment formed on a lever arm 186 secured to one end of a rock shaft 188, which also carries a cam lever arm 190 and a cam roll 192 arranged to engage a corresponding 55 cam groove in the periphery of the drum cam 152. The member 160 of the thread finger is moved into open position to permit the passage of the thread between the thread engaging nubs, and is then closed to hold the thread by the engagement of an upwardly extending arm 194 on the clamping arm 160 with a cam surface 196 provided for this purpose on the bracket 164.

The needle thread (see Figs. 3, 22 and 26) is led from a thread reel 198 over a thread tension 70 member 199 for controlling a reel brake, past a thread tension 200 and through the wax pot generally indicated at 202 to a thread lock 204. The thread reel and reel braking mechanism are similar to those shown and described in the 75 application of Erastus E. Winkley, for shoe sewing

machines, Serial No. 379,413, filed July 19, 1929, and therefore, need not be further described. From the thread lock 204 the thread is carried around a guide roll 206 over the thread take-up roll 208 on the take-up arm 210, and through a second thread tension 212, and from there to the looper. In order to provide for an adjustment of the take-up action of the take-up arm to pull in more or less thread, the guide roll 206 is mounted on a bracket 213 which is adjustably clamped in 10 a slot 215 in the take-up housing. The adjustment of the bracket 213 in the slot 215 tends to move the guide roll 206 toward or away from the guide roll 212, causing more or less thread to be taken up by the movement of the take-up roll 208 15 to the top of its throw.

The take-up of the present machine (see Figs. 26, 27 and 28) is of the rotary type, being arranged to make one complete revolution for each cycle of operations in the machine. With the 20 present construction, a variable speed drive is provided which is arranged to permit a comparatively rapid movement of the take-up lever in taking up and also in giving up the needle thread, while permitting a relatively long dwell to the 25 take-up at the top and bottom of its stroke to cooperate with the sewing instrumentalities. This variable speed driving mechanism comprises a horizontal driving shaft 214 which is mounted parallel to but with its axis offset from the axis 30 of the shaft 216 to which the take-up arm 210 is secured. At its rear end the drive shaft 214 is provided with a worm gear 218 which engages with a worm 220 (see Fig. 4) on the vertical drive shaft 28 of the machine. At its forward end the shaft 35 214 is provided with a crank arm 222 which is connected through a drag link 224 to a crank pin 225 mounted on a disk 226 on the take-up shaft 216, so that accelerating and retarding movements are obtained in the rotation of the take-up 40 during each revolution.

In order to prevent the thread from jumping off from the take-up roll 208 or becoming entangled with the other parts, the take-up is arranged to operate within an enclosing housing 227, 45 the front wall of which is parallel to the plane of movement of the take-up. A passageway for the thread is formed between a stationary plate 228 secured to the front wall of the housing 227, and a flanged disk or shield 229 secured to the 50 end of the take-up shaft 216. A bevel edge disk or button 230 is mounted upon the outer end of the take-up roll 208, and is arranged to bear against the wall of the housing outside of the stationary plate. The thread is thus prevented 55 from jumping off from the take-up roll, being positively guided between the plate 228 and the button 230 on one side, and the shield 229 on the other into engagement with the roll 208. Furthermore, the thread is at all times held in 60 position within the housing to prevent its becoming entangled with other parts of the machine, and the housing also tends to retain the loop of thread in the extended position to which it is brought by the operation of the take-up during 65 the idle revolution of the take-up in stopping the machine.

The thread lock 204 above referred to, is maintained normally in locking position, but is opened momentarily during each sewing cycle, to permit 70 the drawing off of additional thread from the supply, through connections comprising a cam lever 232 provided at one end with a cam roll 234 arranged to ride on the face of the disk 226, and at its other end connected to an endwise 75

movable shaft or plunger 236 for engaging and releasing the thread lock. The plunger 236 is journaled in a bracket 238 in the housing 227, and is provided at its forward end with a tip or head 239 having formed thereon a clamping surface which is arranged to cooperate with a similar surface on a fixed plate indicated at 205 to clamp the thread between them. Two guide screws secured to the member 205 and arranged 10 to project into corresponding recesses in the head 239, serve to position the thread between the two surfaces of the thread lock. A compression spring 241 coiled about the plunger 236 between a shoulder formed on the plunger and a corresponding 15 shoulder of the bracket 238, tends to hold the surfaces of the thread lock normally in locking position. A raised portion on the cam disk 226 engaging with the roll 234, causes the cam lever 232 to move slightly to retract the plunger against 20 the pressure of its spring to release the thread at the desired point in each sewing cycle.

The work support 14 and the pressure foot 16 of the present machine are utilized to feed the work, and to this end are mounted on a feed 25 carriage 244 (see Figs. 7, 8, 9, 10, 29 and 30) which is mounted at its rear end to swing about a fixed pivot 246 on a carrier or slide 248. This carrier is slidably mounted in ways 250 extending towards the rear of the machine, and forms 30 a part of the mechanism for moving the work out of line with the stitch forming devices upon stopping the machine and into line with the stitch forming devices upon starting the machine, as will be hereinafter more fully described.

35 The mechanism for laterally swinging the feed carriage 244 about its pivot 246 to impart the required feeding movements to the work, is similar in its general construction and mode of operation to that shown in the applicant's Patent 40 No. 1,824,063, dated September 22, 1931, but may be briefly described in connection with Figs. 5, 12 and 13 of the drawings. Two pivotally connected feed blocks 252 and 254 are provided which are arranged to slide respectively in a guideway 256 45 formed on the under side of the feed carriage 244 and a guideway 258 formed in a bracket 260 which is adjustable to determine the angular position of the one guideway with relation to the other, so that the desired feeding movement is 50 imparted to the feed carriage 244 by the movement of the feed blocks 252 and 254. The pivotally connected feed blocks 252 and 254 are given a reciprocatory movement in their guideways to 55 impart the required feeding movement to the work by means of a bell-crank 262 pivotally connected at 264 on the machine frame, carrying at one end a roll to engage with a cam on the main drive shaft 28, and having its other end connected by means of a forwardly extending link 266 with the under side of the feed block 254.

In order to provide the necessary angular adjustment of the feed bracket 260 to determine the length of each feeding movement given to the work, the bracket 260 is supported on a vertical post 268 which at its lower end carries a lever arm 270 (see Fig. 12) connected to one end of a feed screw 272 threaded to a feed nut 274. The required adjustment of the feed slide may be had by rotating the feed screw with relation 65 to the nut. In order to enable the operator at will to operate the machine at either of two predetermined rates of feed, a hand lever 276 is mounted to turn on a pivot 278 and carries a gear segment 280 engaging with a corresponding pinion 282 on the feed nut 274. Two adjustable

stop members 284 arranged to engage with a fixed stop pin 286 are mounted to turn on the pivot 278, and are adjustably clamped in position with relation to the hand lever 276 by means of clamping bolts 288. With this construction, the movement of the hand lever 276 to change the adjustment of the feed bracket 260 is limited in each direction by the engagement of the corresponding stop member 284 with the stop pin 286 to secure the exact lengths of stitch which 10 may be required, for instance, in sewing about the shank and toe portions of the shoe. 15

The work support 14 (see Figs. 4 to 10 inclusive, 29, 30, 54 and 55), comprises a curved U-shaped member which is rigidly supported on the feed 15 carriage 244, and has formed therein a rectangular shaped aperture 287 through which the needle and awl are arranged to operate. At its left hand end the work support 14 is secured by a screw 289 to the curved forward end of an arm 20 290 which is provided with a tongue adapted to fit into a corresponding groove 292 in the feed carriage 244, and is clamped rigidly in position thereon by means of a screw 294. At its right hand end the work support is secured to a bracket 25 295 which is formed on the forward end of a plate 296 secured to the feed carriage 244, and which has formed thereon the guideway for the thread cutter slide as hereinafter described. The plate 296 is provided with tongues arranged to 30 engage in corresponding grooves 298 in the side of the feed carriage, and is secured thereto by two screws 300.

The presser foot 16 is formed on a curved member 303 which is rigidly secured at each 35 end to the two arms of the forked upper end of a presser foot support member or bar 304. A rectangular shaped aperture 305 is provided in the presser foot 16 to provide a passage for the needle and awl through the presser foot. The presser 40 foot bar 304 is carried on a pair of parallel links 306 pivotally mounted on a supporting post 308 which forms an integral part of the feed carriage 244, so that the presser foot bar 304 is permitted to move in a substantially lengthwise 45 direction to bring the presser foot into and out of clamping engagement with the work. An arm 310 forming an integral part of the lower link 306 and extending downwardly therefrom, is connected to a tension spring 312 which tends to 50 force the presser foot downwardly at all times into engagement with the work. The presser foot is locked in clamping engagement with the work during each feeding movement by means of a locking wedge construction, which comprises a 55 tapered wedge block 314 which is connected by means of a link 316 to move with the presser foot bar 304, and is slidably mounted in a wedge box formed in the plate 296. The wedge box (see Figs. 6 and 14) comprises a recess 318 formed 60 in the inner side of the plate 296, and is shaped to provide two upwardly converging surfaces 322 and 324 against which the wedges act to secure the required wedging or locking effect. A second wedge block 320 is also mounted in the wedge 65 box 318, and is arranged when moved downward to wedge the two blocks against the converging cam surfaces 322 and 324 to lock the presser foot in clamping position. The wedges are held in position in the box against the adjacent surface 70 of the feed carriage 244 to which the plate 296 is secured, and against the presser foot bar 304. The position of the locking wedge 320 is controlled by means of a link 326 provided at its upper end with an offset portion which extends 75

through a guiding slot 328 formed in the plate 296 into engagement with the wedge block 320. The lower end of the link 326 is connected to a presser foot actuating lever 330 by means of a pivot pin 332 which is adjustably clamped in a slot 334. The presser foot actuating lever 330 is mounted to swing about a pivot shaft 336 mounted on the carrier 248 (see Figs. 7, 8 and 15), and is provided with a dog 338 which is arranged 10 to engage with the lower end of the presser foot bar 304. The dog 338 is pivotally secured to the presser foot actuating lever 330 and is held adjustably in position by means of a clamping screw 340 extending through a slot in the dog. With 15 this arrangement of the parts, as the presser foot actuating lever 330 is moved about its pivot to cause the dog 338 to engage with and lift the presser foot bar 304 and the presser foot 16 to release the work, the link 326 being connected 20 to the actuating lever 330 at a point more remote from the fulcrum or pivot 336, causes the locking wedge 320 to be moved upwardly at a more rapid rate to release the wedge 314 and permit it to be moved upwardly with the presser foot bar 304.

The presser foot actuating lever 330 is actuated during each cycle of operations to raise the presser foot and release the work during the return movement of the feed carriage through connections which comprise the cam lever 342 pivotally mounted at 344 on the machine frame, and provided with cam rolls 346 and 348 which are located on opposite sides of the pivot 344 and engage respectively with cam surfaces 350 and 351 (see Figs. 6 and 16) formed on the periphery of the cam disk 137. A link 352 is connected at one end to an arm of the lever 342 and at its other end to a dog 354 which is pivotally connected to one arm of a bell-crank lever 356 loosely mounted to turn on the pivot shaft 336 of the presser foot actuating lever 330, and which is provided with a cam surface 358 arranged upon movement of the dog about its pivot to come into locking engagement with a corresponding surface formed on a short arm 360 formed integrally with the presser foot actuating lever 330. The bell-crank lever 356 is held in an adjusted angular position to cause the dog 354 to engage with the arm 360 and raise the presser foot actuating lever 330 and presser foot 316 a predetermined amount through connections comprising a link 362 which is connected to a downwardly extending arm of the bell-crank 356. At its rear end the link 362 is arranged to slide in a sleeve 364 screw-threaded in a bracket 366 fastened to the carrier 248 and held adjustably in position by means of a lock nut 368. A collar 370 secured to the link is arranged to engage with the sleeve 364, and limits the rearward movement of the link under the influence of a compression spring 372 coiled about the link between the sleeve 364 and a nut 374 on the rear end of the link. With this arrangement of the parts, the angular position of the bell-crank 356 may be readily adjusted to determine the amount of lift given to the presser foot by an adjustment of the position of the sleeve 364 in the bracket 366.

The presser foot actuating lever 330 is moved yieldingly downward to disengage the dog 338 from the lower end of the presser foot bar 304, and to cause the locking wedge 320 to be held yieldingly in locking engagement with the wedge 314 by means of a small spring 376, Fig. 8, which is connected at one end to the machine frame 70 and at its other end to a downwardly extending

arm 378 formed on the hub of the presser foot actuating lever 330.

During the operation of the machine, starting with the parts in the position shown, for instance, in Fig. 8, with the presser foot in clamping engagement with the work, the movement of the presser foot actuating lever 342 will cause the dog 354 during each sewing cycle to move about its pivot and bring the cam surface 358 into locking engagement with the corresponding surface on the arm 360. The further movement of the cam lever 342 now acts through these connections to swing the presser foot actuating lever 330 around its pivot, acting first through the link 326 to raise the locking wedge 320, and thereafter through the engagement of the dog 338 with the lower end of the presser foot bar 304 to raise the presser foot from the work.

In the machine shown in the drawings, the carrier upon which the feed carriage, presser foot and work support are mounted is arranged, upon the release of the foot treadle in stopping the machine, to move outwardly so that the work is moved from the path of the needle and awl, and the needle thread is carried into a position where it will not be placed in the hook of the needle. The cam shaft and the parts driven thereby including the needle, awl and shuttle, are then brought gradually to a stop by means of the clutch brake above described. This arrangement of the operating mechanism enables the sewing operation to be discontinued almost instantaneously, and it is not necessary to stop the sewing devices in any particular position.

The outward or forward movement of the feed carriage 244 and carrier 248 in stopping the machine is arranged to cause the presser foot automatically to be lifted to disengage the work, so that the work may be readily removed from the machine by the operator. For this purpose, an upwardly extending lever arm 379 (see Figs. 7, 8, 10 and 12) is formed on the hub of the presser foot actuating lever 330, and is arranged during the forward movement of the carrier 248 on which the lever 330 is carried to engage with a stationary pin 380 to rotate the presser foot actuating lever 330 about its pivot 336 and raise the presser foot. The pin 380 forms a part of and is eccentric to a pin 381 which is mounted in a slidable sleeve member 382 journaled in the machine frame, and is rigidly held in the desired angular position with relation to the sleeve to secure the required adjustment of the eccentric pin 380 by the clamping action of a collar 383 at the inner end of the pin and a nut 384 threaded on the outer end of the pin. The sleeve 382 is held yieldingly in advanced or operative position with the pin 380 in the path of the lever arm 379 by means of a compression spring 385 seated in a recess or bore in the frame parallel to the pin 381, and arranged to bear against a small pin 386 offset from the sleeve 382. The sleeve is held against angular movement by the engagement of a projection or key 387 on the sleeve with a slot in the frame.

To enable the operator to place a new piece of work in position on the work support and cause it to be clamped securely in position while the feed carriage is in its advanced inoperative position, mechanism is provided under the control of the operator for retracting the sleeve 382 and pin 381 to release the presser foot actuating lever 330 and permit the presser foot to be moved downwardly into clamping position under the pressure of its spring 312. This mechanism (see Fig. 1) comprises a foot treadle 388 pivotally mounted 75

on the machine and provided with an upwardly extending link 389 which is connected at its upper end to a guiding lever 390, and to a second link 391 which is in turn connected to the lower end 5 of a slide 392 arranged for vertical movement in a guideway formed in the machine frame. A block 394 (Figs. 8, 11 and 12) rigidly secured to the upper end of the slide 392 is provided with a cam surface 395 arranged to engage with a 10 correspondingly cam-shaped projection 396 formed on the sleeve 382, so that the downward movement of the slide upon the actuation of the foot treadle by the operator, causes the sleeve 382 and pin 380 to be withdrawn against the 15 pressure of the spring 385 to release the lever arm 379 and the presser foot actuating lever 330.

In order to permit the operator during the 20 operation of the machine to raise the presser foot and release the work, connections are provided 25 which are controlled by the actuation of the foot treadle 388 when the feed carriage 244 is in its retracted or operating position to raise the presser foot, these connections (see Figs. 8, 10, 12 and 16) comprising a lever arm 415 rigidly secured to turn 30 with the presser foot lifting lever 330, and provided at its free end with an offset projection or pin which is arranged to move into the path of a projection 417 on the slide 392 as shown in Fig. 8, when the feed carriage 244 is retracted 35 upon starting the machine. If the foot treadle 388 is now depressed by the operator, the downward movement of the slide 392 will bring the projection 417 into engagement with the offset portion of the lever 415 to depress the lever and 40 rotate the presser foot actuating lever 330 about its pivot to raise the presser foot.

The mechanism by which the carrier 248 is advanced upon stopping the machine, and is again moved into operating position in starting 45 the machine, comprises a cam disk 397 which is secured to a vertical drive shaft 398 journaled in bearings in the machine frame, and is provided on its under side with a cam groove arranged to receive a roll 399 mounted on the rear end of the 50 carrier 248. The drive shaft 398 and cam disk 397 are rotated through one-sixth of a revolution at the beginning of each sewing operation to cause the carrier to be retracted, bringing the work support, presser foot and work into operative position, and are again rotated through one-sixth of a revolution upon releasing the starting and stopping treadle to advance the carrier and work to 55 inoperative position, by means of a Geneva stop motion, the star wheel 400 of which is secured to the upper end of the drive shaft 398, and is provided with six slots 401 which are arranged to receive an actuating pin or bolt 402 mounted in the continuously rotating gear 54. During the 60 normal operation of the machine while sewing, the bolt 402 is held in raised position out of engagement with the wheel 400, as shown in Fig. 12, by the engagement of a latch 403 pivoted on the upper face of the gear 54 with a notch in the bolt. A spring 405 fastened on the upper face of the 65 gear, engages with a small pin on the latch to hold it normally in locking engagement with the bolt 402. Upon the release of the bolt by the latch 403, the bolt is moved downwardly into operative position to engage in the slot 401 of the 70 wheel 400 by means of a compression spring 406 (see Fig. 16) bearing at its lower end on a laterally extending pin on the bolt, and secured within a recess in the gear 54. The latch 403 is actuated to release the bolt 402 and cause the Geneva wheel 75 400 and cam 397 to be rotated through one-sixth

of a revolution to advance or retract the carrier by means of a lever arm 407 which is secured to the upper end of a rock shaft 408, and is arranged when rendered operative to move into the path of and trip the latch. The bolt is returned to raised position where it is again engaged by the latch 403 during the continued rotation of the gear 54 by means of a fixed cam 409 (see Figs. 6, 10 and 16) which is formed on a bracket 410 on the machine frame, and engages an arm 411 projecting laterally from the upper end of the bolt 402. The rock shaft 408 and arm 407 are normally held out of operative engagement with the latch 403, against the pressure of a spring 412 (see Figs. 10 and 16) secured at one end to the 15 machine frame, and at its other end to an arm 413 on the rock shaft, by means of a latch 414 which is pivotally mounted on an arm secured to the rock shaft 408, and is normally held in position to engage with a fixed abutment 416 on the 20 machine frame by means of a small spring 418. The latch 414 is tripped by the actuation of the starting and stopping treadle, as hereinafter described, to permit the rock shaft 408 and arm 407 to rotate under the pressure of the spring 412, to 25 render the Geneva motion operative to advance or retract the slide as above described.

The shaft 408 and arm 407 are immediately returned to inoperative position with the latch 414 in engagement with the abutment 416 by means 30 of an arm 420 formed on the shaft 408, and arranged to engage with one of six abutments 422 formed on the under side of the wheel 400.

Connections are provided from the starting and stopping treadle which are arranged upon de- 35 pressing the treadle in starting the machine to trip the latch 414 to retract the carrier 248, and upon releasing the starting and stopping treadle to again trip the latch 414 to return the carrier 248 to its advanced inoperative position. These 40 connections comprise a slide 428 (Figs. 9 and 16) which is arranged for vertical movement in a guideway 430 in the machine frame, and is connected by a link 432 (Fig. 1) to the upper end of the treadle actuated link 42 to move downwardly 45 as the treadle is depressed, and upwardly as the treadle is released. At its upper end the slide 428 is provided with a head 434 which engages between two prongs formed on a trip lever 436 pivotally mounted at 438 on the machine, and so ar- 50 ranged that the depressing of the starting treadle 38 will move the trip lever past a vertical upright position towards the left from the position shown in Fig. 16, and the releasing of the foot treadle in stopping the machine will cause this lever again 55 to pass a vertical position to that shown in this figure. The trip lever 436 is limited in its movement in each direction by the engagement of a fixed pin 440 with the ends of an arcuate slot 442 formed in the lever 436. 60

The mechanism through which the actuation of the trip lever 436 is rendered operative to trip the latch 414 in starting and stopping the machine (see Figs. 16 to 21 inclusive), comprises a lever arm 444 which is pivotally secured to a 65 bracket 446 on the carrier 248, and is normally held by a small spring 448 in a depressed position which is adjustably determined by the engagement of a set screw 450 on the lever arm with a step formed on the bracket 446. A member 452 70 is pivotally secured to the outer end of the lever arm 444, and is provided with an elongated supporting surface 454 arranged to underlie the end of the latch 414 for all positions of the carrier 248, and is normally held in an upright position 75

by means of a small spring 456 which tends to hold a projecting nub of the member in engagement with a pin 457 on the lever arm 444. The movement of the trip lever 436 past the vertical position upon actuating the treadle 38 to start or stop the machine, is rendered operative to raise the lever 444 and cause the bearing surface 454 of the member 452 to engage with and trip the latch 414 through a mechanism which is arranged 5 to be rendered operative upon depressing the treadle only if the carrier is in its advanced or inoperative position, and to be rendered operative upon releasing the starting treadle only if the carrier 248 is in its retracted or operating position. This mechanism comprises two dogs 458 and 460 which are pivotally mounted on a shaft 462 supported on the bifurcated outer end of the lever arm 444. The dog 458 is provided with an arcuate slot cut in the left side of the dog (see Figs. 18 and 19) and arranged to receive a pin 464 secured to the lever arm 444, and the dog 460 is similarly provided with an arcuate slot cut in the right side of the dog (see Fig. 20) arranged to receive a pin 466 secured to the lever arm 444. 10 A spring 468 coiled about the pivot shaft 462 engages with the dogs 458 and 460 to hold these members yieldingly in the vertical position shown in Fig. 18. With this arrangement of parts, the movement of the trip lever 436 to the left upon 15 starting the machine, with the carrier 248 in its advanced or inoperative position, will cause the dog 458 held rigidly in its vertical position by the pin 464 to be engaged by and ride upwardly on the V-shaped tip of the trip lever 436 to raise the lever arm 444 and member 452 to trip the latch 414. Similarly, the movement of the trip lever 436 to the right to the position shown in Fig. 16, upon releasing the starting treadle, with the carrier 248 in its retracted or operating position, 20 will cause the dog 460 held rigidly in vertical position by the pin 466 to engage with and ride upwardly on the V-shaped surface of the trip lever 436 to raise the lever arm 444 and member 452 to again trip the latch 414. 25 If, however, the Geneva stop motion for advancing or retracting the carrier 248 should get out of time with the starting and stopping mechanism, as for instance might happen if the operator were to depress the treadle and then release it 30 immediately before the trip mechanism for the Geneva stop motion were reset, the connections above described for throwing the Geneva stop motion into operation upon again depressing the foot treadle are rendered inoperative, so that the carrier 248 will be left in its retracted or operative position. With the carrier 248 in its retracted position, the downward movement of the treadle 38 in starting the machine, causes the trip lever 436 to engage the dog 460, and due to the pin and 35 slot construction, as illustrated in Fig. 20, merely acts to swing this dog about its pivot 462 against the pressure of the spring 468 without causing the latch 414 to be tripped, so that the Geneva stop motion will not at this time be rendered operative to change the position of the carrier 248. Similarly, where for some reason the carrier is in its advanced or inoperative position while the machine is running, the movement of the trip lever 436 in the opposite direction upon releasing the 40 foot treadle, will engage with and cause the dog 458 to be moved about its pivot again without tripping the latch 414.

The starting and stopping clutch of the machine is arranged upon depressing the starting treadle 38 to start the machine at a comparatively

slow rate as the carrier 248 is brought into operative position, and then to bring the machine up to speed, and when the starting treadle is released upon stopping the machine, to operate the machine momentarily at a relatively slow rate as the carrier 248 is moved outwardly to its inoperative position. For this purpose the driving clutch member 36 is controlled, as best shown in Figs. 1 and 2, by means of a sleeve 470 which is loosely mounted for a limited movement lengthwise of the sleeve hub of the driving clutch member 36, and is provided with two flanges 472 forming a track to receive rolls mounted on the forked end of the bell-crank control lever 44. A compression spring 476 coiled about the sleeve 470 and abutting at one end against a flange 472 and at its other end against the clutch member 36 tends to hold the sleeve in a retracted position on the sleeve hub of the clutch member 36 and in engagement with a flange 478 secured to the rear end of the hub. 15 The free end of the bell-crank control lever 44, actuated as previously stated, from the starting and stopping treadle 38 of the machine through the link 42, is connected to the link through a pin and slot arranged to permit some lost motion in the operation of the parts. When the treadle is released by the operator and permitted to move to its raised or inoperative position under the influence of its spring 50, the bell-crank clutch control lever 44 is rotated about its pivot tending 20 to move the sleeve 470 rearwardly into engagement with the collar 478, to disengage the clutch member 36 from the clutch member 30. 25

When the treadle is depressed in starting the machine, the bell-crank control lever 44 is rotated about its pivot to advance the sleeve 470, causing the spring 476 to be compressed, and forcing the clutch member 36 yieldingly into engagement with the member 30, the relatively light frictional engagement of the clutch members 30 and 36 permitting some slippage between these members, so that the machine is operated at a relatively slow rate of speed. As the treadle is depressed to its fullest extent, the forward end of the sleeve engages positively with the clutch member 36 to force the two members of the clutch into rigid clamping engagement, thus bringing the machine up to speed. In order to secure a momentary slow speed of operation of the machine upon releasing the starting treadle, 30 a latch lever 482 is pivotally mounted at 484 on the machine frame, and is provided with a detent pin 486 arranged to engage with a corresponding detent 488 adjustably secured to the bell-crank lever 44, these parts being arranged to arrest the movement of the bell-crank actuating lever 44 about its pivot upon releasing the treadle 38, so that the sleeve 470 is held in an intermediate position with the clutch member 36 still in engagement with the clutch member 30 under the yielding pressure of the spring 476. The latch lever 482 is connected by a link 490 to one arm of a bell-crank lever 492 which is pivotally mounted on the machine and is provided with a vertically disposed arm which projects into the path of an abutment 494 on the carrier 248. A spring 496 connected at one end to the link 490 and at the other end to a fixed point on the machine, tends to hold the link 490 and the latch lever 482 in a depressed position with the detent pin 486 in the path of the bell-crank clutch actuating lever 44. With this arrangement of parts, it will be seen that during the operation of the machine with the carrier 248 in its retracted or operating position, the latch 482 is held in a depressed or

operative position under the pressure of the spring 496 to arrest the movement of the clutch actuating lever 44 to its full inoperative position. When the treadle 38 is released to stop the machine, the sleeve 470 will move away from the clutch member 36 to the intermediate position determined by the engagement of the detent 488 with the detent pin 486, so that the driving clutch member 36 will be held in engagement with the clutch member 30 under the relatively light pressure exerted by the spring 476, thus materially reducing the speed of operation. At the same time the Geneva stop motion will be thrown into operation as above described to move the carrier 10 to inoperative position. As the carrier advances, the abutment 494 on the carrier engages the bell-crank 492 to raise the latch 482 to inoperative position, and permits the clutch to be entirely disconnected by the continued movement of the bell-crank 44 and treadle 38 under the influence of the spring 50.

The present machine is provided with thread cutting and holding devices including a cutter 500 which is rendered operative upon stopping the machine to cut both threads beneath the work, a clamping device arranged to hold the shuttle thread beneath the work, and a clamp 504 arranged to grip the needle thread above the work. The cutter 500 as best shown in Figs. 54 and 55, 25 comprises an arcuate-shaped member which is arranged to slide against the under side of the U-shaped work support 14 across the aperture 287 through which the needle and awl operate, and is rigidly secured at its right hand end to 30 a slide 505 mounted in a guideway 507 which is formed in the bracket 295 on the plate 296, and forms a continuation of the curve of the work support 14. The cutter slide 505 is connected to a bell-crank actuating lever 508, pivotally mounted at 510 on the plate 296, by means of a short link 506 which is provided with a socket arranged to engage with a knob 509 on the slide. The other arm of the bell-crank lever 508 is arranged to engage in a socket formed in a bracket 512 secured to the machine frame, so that as the 40 carrier 248 and feed carriage 244 are advanced to inoperative position upon stopping the machine, the advancing movement of the pivot 510 will cause the bell-crank lever to swing about its pivot to advance the cutter. This operation is timed to cause the knife to move across the aperture 287 in the work support, and sever the threads before the take-up has completely pulled in the stitch, so that a loop of needle thread is 45 still below the work, causing both the needle and shuttle threads to be severed closely beneath the work.

With the present construction, a clamping device is provided to hold the severed end of the shuttle thread during the formation of the first stitch or stitches of the next sewing operation. This clamping device comprises a spring clip 515 secured by a screw 516 to the supporting member 290, and arranged to engage one side of the U-shaped supporting member 14. In order to cause the shuttle thread to be brought into engagement with the clip upon stopping the machine, the cutter member 500 is provided on its under side with a tongue 514 which projects beneath and beyond the cutting surface, so that the advancing movement of the cutter causes the tongue 514 to engage with and push the shuttle thread between the spring clamp 515 and the adjacent side wall of the work support 14.

75 The thread clamp 504 for gripping the needle

thread (see Figs. 5, 9, 10, 13, and 54 to 57) comprises a finger which is formed on one end of an arcuate-shaped member 517 which is mounted to slide in a guideway formed in a bracket 513 on the presser foot bar 304, and is provided at its rear end with a laterally projecting nub 518a. The thread clamp 504 and its supporting slide 517 are supported and guided to cause the finger to move across the aperture 305 in the presser foot in a slot formed between the presser foot 16 and 10 an overlying arm 519 which are arranged to cooperate with the finger 504 when rendered active to clamp the needle thread. When the feed carriage 244 carrying with it the presser foot 16 and bracket 513 is advanced to inoperative position 15 upon stopping the machine, the nub 518 is brought into contact with and is held in a retracted position by means of an arcuate-shaped stop 520 rigidly mounted on the machine frame, thus causing the member 517 and finger 504 to 20 move relatively to the presser foot 16 across the aperture to engage with and grip the needle thread between the gripping jaws formed by the adjacent surfaces of the presser foot and the arm 519.

25 Since the threads are severed and the needle thread clamp 504 is actuated to grip the needle thread before the take-up has completed its upward stroke to draw in the needle loop, it has been found necessary to provide mechanism for 30 releasing the thread lock 204 at this time to permit additional thread to be drawn off from the supply to take the place of that which would normally be taken up from the work as the take-up continues to rotate. This mechanism (see Figs. 35 4, 8, 10, 16 and 22) comprises a lever 521 pivoted at 522 on the machine frame, one arm being arranged to engage with an abutment 523 on the thread lock actuating cam lever 232, and the other arm being connected to a horizontal lever 40 arm 524 through the engagement of a roll 525 on the arm 524 with a cam slot 526 formed in the adjacent arm of the lever 521. The arm 524 is rigidly secured to a vertical post or shaft 527, which is journaled in the machine frame, and at 45 its lower end is provided with an arm 528 which engages in a slot 529 in the carrier 248. With this construction and arrangement of parts, it will be seen that the advancing movement of the carrier 248 to move the work out of the path of the 50 needle in stopping the machine, will cause the shaft 527 to be rocked, moving the roll 525 rearwardly in the cam slot 526, so that the actuating lever 521 is moved about its pivot to retract the cam lever 232 against the pressure of the spring 55 241 and release the thread lock. When the carrier 248 is retracted in starting the machine to move the work into operative position, the rock shaft 527 will be rocked about its pivot in an opposite direction to swing the actuating lever 521 60 out of engaging contact with the abutment 523 on the cam lever 232 and allow the thread clamp again to be moved into operative position under the influence of its spring 241.

In order to insure the proper operation of the 65 take-up to pull in the loop of needle thread in the formation of the first stitches at the beginning of a new sewing operation, the needle thread clamping mechanism is constructed and arranged to move the member 517 and clamp 504 out of 70 clamping position to release the severed end of the thread only after the completion of one or more stitches. This mechanism for releasing the needle thread gripper comprises a vertically arranged lever arm 530 (see Figs. 5, 9 and 10) piv- 75

oted at its lower end to the machine frame, and at its upper end provided with an arcuate bearing surface 531 arranged upon the forward movement of the lever to engage with the laterally offset nub 518 to advance the member 517 and clamp 504 to inoperative position. A compression spring 532 seated at one end in a socket of the machine frame, and at its other end in a socket 533 in the lever 530, tends at all times to move the lever forwardly to engage with and move the clamp 504 to inoperative position. A stop screw 534 adjustably mounted in a bracket 535 on the machine frame, is arranged to engage with and positively limit the forward movement of the lever 530 about its pivot. The lever 530 is normally held in a retracted position out of contact with the member 517 by means of a dog 536 pivotally mounted on the lever 530 and provided with a laterally extending projection 537 arranged to engage with a notch formed in a block 538 formed on the arm 290 secured to the feed carriage 244 (see Fig. 9). A spring 539 secured at one end to the dog and at its other end to the lever arm, tends to rotate the dog about its pivot in a direction to hold the projection 537 at all times in engagement with the block 538.

As the feed carriage 244 is retracted upon starting the machine to bring the work into operative position, the retracting movement of the lever 530 caused by the engagement of the recess in the block 538 carried by the feed carriage 244 with the offset projection 537 of the dog 536, causes the dog to be brought into operative engagement with mechanism which acts after the completion of the first stitch to rotate the dog on its pivot against the pressure of the spring 539 to release the lever 530, so that the lever is again moved forward under the pressure of its spring 532 to engage with and move the member 517 and clamp 504 to inoperative position. This mechanism comprises a cam lever 540 arranged at its rear end to ride on a cam 542 and at its forward end provided with a pawl 544 arranged to engage with a series of ratchet teeth 546 on the dog 536. A spring 547 secured at one end to the cam lever 540 and at its other end to the machine frame, tends to hold the lever in yielding engagement with its cam. A pin 548 on the cam lever 540 engages with a tail piece on the pawl to limit its forward movement under the influence of a spring 550 connected at one end to the dog, and at its other end to the cam lever 540. The parts are so arranged that the pawl 544 is out of operating contact with the ratchet 546 when the lever 530 is in advanced position, but as the lever 530 is carried rearwardly upon movement of the feed carriage 244 and presser foot 16 into operative position, the continuously oscillating pawl is brought into engagement with the ratchet 546, and acts in timed relation to the operation of the cam shaft to rotate the dog about its pivot and release the lever 530 after the completion of the first stitch.

The present machine is provided with a welt guiding and cutting mechanism which is similar in many respects to that disclosed in the applicant's Patent No. 1,774,498, dated September 2, 1930. This mechanism comprises a cutter member 556 which is mounted to slide in a slot 558 in a bracket 559 formed integrally with the member 303 which carries the presser foot 16, and is arranged to intersect the guideway 554 for the welt also formed integrally with the member 303 at an angle to form a bevelled end to the welt. A cover plate 561 screwed to the bracket 559

serves to close the slot 558 and the lower end of the welt guideway 554 to hold these elements in position. At its upper end the cutter member 556 is connected to one arm 560 of the bifurcated cutter actuating lever 562 secured to a short rock shaft 564 which is journaled in a bearing formed in the right hand fork of the presser foot bar 304 as viewed from the front of the machine. A heavy spring 567 coiled about the bearing for the rock shaft 564 and engaging at one end with a pin 10 on the lever 562, tends at all times to depress the lever 562 and cutter member 556 to sever the welt. As in the applicant's patent above referred to, the lever 562 is held in a raised position normally during the operation of the machine through mechanism which is arranged to engage with the second arm 568 of the bifurcated lever 562 to prop the lever and cutter member 556 in raised position, and is rendered operative automatically to sever the welt at a point which will cause the two ends of the welt to fit closely together by means of a feeler member 570 which contacts with the leading end of the welt on the shoe. With the present construction, the lever 562 is held in its raised position by means of a toggle lever consisting of a link 572 which is punched to receive the tapered end of the arm 568, and a link 574 pivotally connected to the link 572, and at its lower end to the presser foot bar 304. The toggle links 572 and 574 are normally locked in straightened position slightly to the right of the line of centers as shown in Fig. 37, by the engagement of adjacent surfaces 516 formed respectively on the toggle links 572 and 574, the links normally being held in this position by means of a small spring 578 connected at one end to the presser foot bar 304, and at its other end to the toggle link 574. The feeler member 570 is pivotally secured to a vertically movable slide 580, and is provided at its upper end with a laterally offset 40 butt 582 which is arranged in the depressed or operative position of the trip mechanism to contact with the upper end of the toggle link 572, so that the movement of the feeler member 570 about its pivot upon engagement with the leading end of the welt, will cause the butt 582 to engage with and rotate the toggle link 572 to break the toggle and permit the lever 562 and cutter member 556 to descend under the pressure of the spring 567 to sever the welt. The feeler member 570 is normally held in a vertical position out of contact with the toggle member 572 in engagement with a pin 586 on the slide 580 by means of a small spring 584. The slide 580 may be locked in raised or inoperative position during the normal operation of the machine to prevent an accidental operation of the welt cutter, by engagement of a latch 588 pivotally mounted on the arm 566 of the cutter actuating lever 562 with a projecting nub 590 on the upper end of the slide 60 580, and is released by the operator to permit the slide 580 and the feeler 570 to be depressed into operative position toward the end of the sewing operation, by means of a laterally extending manually operable lever arm 592 formed on the hub of 65 the latch 588.

With the present construction, the feeler member 570 for automatically tripping the welt cutter, is constructed and arranged to permit an automatic adjustment of the feeler member vertically in accordance with variations in the thickness of the shoe sole, and laterally to conform to the contours of the shoe upper, to eliminate the possibility that the finger will be actuated prematurely by contact with some part of the shoe 75

to cut the welt. In order to secure a sensitive vertical adjustment of the feeler member 570 in accordance with the thickness of the shoe sole, the slide 580 is mounted to move relatively to a second slide 594 which is in turn mounted for vertical movement on a supporting bracket 596 formed on the forked portion of the presser foot bar 304. The slide 580 is cut away on its rear side to receive the slide 594, and is provided with a downwardly extending tongue 598 which engages with a corresponding track formed in the rear side of the slide 594. The slide 594 is also grooved to receive two laterally extending trunnions or bars 600 which engage with corresponding slots 602 in the bracket 596. A light spring 604 seated in a recess 606 in the bracket 596 and engaging at its lower end with a pin 608 on the tongue 598, tends to move the slide downwardly to hold the feeler member 570 in yielding contact with the work. In order to secure an automatic lateral adjustment of the feeler member to conform to the contours of the shoe upper, the lower end of the feeler member is formed as a separate member 610 which is hinged at 612 on a bracket 613 on the member 570 to move rearwardly away from the shoe, and is normally held in a straightened position by a small compression spring 614 inserted between the lower end of the slide 580 and the hinged member 610. The work engaging part 610 of the feeler member 570 is also adjustable longitudinally in the line of feed to permit a close adjustment of the timing in the operation of the cutting knife with relation to the leading end of the welt, so that a tight joint may be formed between the two ends of the welt. To this end the bracket 613 is mounted to swing in the line of feed about the pivot 615 on which the feeler member 570 is mounted to turn, and is held adjustably in position by means of a clamping screw 617 which extends through a transverse slot 619 in the member 570, and is threaded into the bracket 613.

The cutter actuating lever 562 is automatically raised upon starting the machine to raise the cutter knife 556 out of the path of the welt and to reset the toggle links in straightened position, by means of a cam lever 616 which is pivoted at 618 to the machine frame, and carries on one arm a roll arranged to engage with a cam groove 620 formed in the face of a cam disk on the shaft 52, and on its other arm is provided with an engaging surface 622 which is arranged to come in contact with the downwardly extending arm 624 secured to one end of the rock shaft 564. As the feed carriage 244 and carrier 248 are retracted into operative position upon starting the machine, the arm 624 is brought into the path of movement of the bearing surfaces 622 of the cam lever 616, causing the arm 624 and shaft 564 to be rocked to raise the lever arm 562 and cutter member 556, where they are held by the locking of the toggle links 572 and 574 in their straightened position.

The take-up mechanism and the welt cutting mechanism disclosed in the present application form the subject-matter of divisional applications Serial No. 719,886 filed April 10, 1934 and Serial No. 747,536 filed October 9, 1934.

The invention having been described, what is claimed is:

1. A sewing machine having, in combination, work supporting and stitch forming devices including a needle, and means rendered operative upon stopping the machine and acting during the

continued actuation of the stitch forming devices to move the work out of the path of the needle.

2. A sewing machine having, in combination, stitch forming devices including a needle, clamping devices for supporting the work in the machine, and means rendered operative upon stopping the machine for actuating said clamping devices to move the work out of the path of the needle.

3. A sewing machine having, in combination, work supporting and stitch forming devices including a needle, a work support, and a presser foot cooperating therewith to position the work in the machine, and means rendered operative upon stopping the machine for actuating said work support and presser foot to move the work out of the path of the needle.

4. A sewing machine having, in combination, stitch forming devices including a needle, work supporting devices including a work support and a presser foot cooperating therewith to position the work in the machine, and means rendered operative upon stopping the machine for actuating said work support and presser foot to move the work out of the path of the needle and to release the work.

5. A sewing machine having, in combination, stitch forming devices including a needle, work supporting devices including a work support and a presser foot, a carriage on which said work support and presser foot are mounted, and means rendered operative upon stopping the machine for actuating said carriage to move the work out of the path of the needle.

6. A sewing machine having, in combination, stitch forming devices including a needle, work supporting devices including a work support and a presser foot, a carriage on which said work support and presser foot are mounted, means acting normally to hold the presser foot and work support in clamping engagement with the work, and means rendered operative upon stopping the machine for actuating said carriage to move the work out of the path of the needle and to move the presser foot and work support out of clamping engagement with the work.

7. A sewing machine having, in combination, stitch forming devices including a needle, work supporting devices including a work support and a presser foot, a carriage on which said work support and presser foot are mounted, means acting normally to hold the presser foot and work support in clamping engagement with the work, means rendered operative upon stopping the machine for actuating said carriage to move the work out of the path of the needle, mechanism rendered operative by said outward movement of the carriage to raise the presser foot out of clamping engagement with the work, and means controlled by the operator for actuating said mechanism to permit the presser foot to move into clamping position with the carriage in its outward inoperative position.

8. A sewing machine having, in combination, stitch forming devices including a needle, work supporting devices including a work support and a presser foot, a carriage on which said work support and presser foot are mounted, means acting normally to hold the presser foot and work support in clamping engagement with the work, means rendered operative upon stopping the machine for actuating said carriage to move the work out of the path of the needle, mechanism rendered operative by said outward movement of the carriage to raise the presser foot out of

clamping engagement with the work, said mechanism comprising a presser foot lifting lever pivotally mounted to move with the feed carriage, a stationary member arranged to engage with and 5 cause the presser foot lever to raise the presser foot during the advancing movement of the carriage, and means controlled by the operator for moving the member out of engagement with the presser foot lever to permit the presser foot 10 to move into clamping position with the carriage in its advanced inoperative position.

9. A sewing machine having, in combination, stitch forming devices including a needle, work supporting devices including a work support and a 15 presser foot, a carriage on which said work support and presser foot are mounted, means acting normally to hold the presser foot and work support in clamping engagement with the work, means rendered operative upon stopping the machine 20 for actuating the carriage to move the work out of the path of the needle, means rendered operative by said outward movement of the carriage to raise the presser foot out of clamping engagement with the work, a manually operable presser 25 foot control member, and actuating connections from said control member rendered operative by the actuation of said member during the operation of the machine to lift the presser foot alternatively with the carriage in its stopped position 30 to permit the presser foot to move into clamping position with the work.

10. A sewing machine having, in combination, work supporting and stitch forming devices including a needle, and mechanism acting when 35 rendered operative in timed relation to the operation of the stitch forming devices to move the work out of the path of the needle.

11. A sewing machine having, in combination, work supporting and stitch forming devices including a needle, a work support, and a presser 40 foot cooperating therewith to position the work in the machine, and means acting in timed relation to the operation of the stitch forming devices rendered operative upon stopping the machine and during the continued operation of the 45 stitch forming devices for actuating said work support and presser foot to move the work out of the path of the needle.

12. A sewing machine having, in combination, 50 stitch forming devices including a needle, work supporting devices including a work support and a presser foot, a carriage on which said work support and presser foot are mounted, means for imparting lateral feeding and return movements to the carriage, and means acting automatically upon stopping the machine to advance the carriage in timed relation to the operation of the stitch forming devices to move the work out of the path of the needle.

13. A sewing machine having, in combination, 60 stitch forming devices including a needle, work supporting and feeding devices including a work support and a presser foot, a feed carriage on which the presser foot and work support are mounted, a carrier to which the feed carriage is pivotally secured, means for moving the feed carriage laterally about its pivot to impart the required feeding movements to the work, and means rendered operative in stopping the machine to advance the carrier and feed carriage 65 to move the work out of the path of the needle.

14. A sewing machine having, in combination, 70 stitch forming devices including a needle, work supporting devices including a work support and a presser foot, a feed carriage on which the work

support and presser foot are mounted, a carrier on which the feed carriage is mounted, mechanism arranged when rendered operative alternatively to advance or retract the carrier in timed relation to the operation of the machine, starting and stopping mechanism for the machine arranged upon stopping the machine to render said carrier actuating mechanism operative to advance the carrier and feed carriage to move the work out of the path of the needle, and upon 10 starting the machine to retract the carrier and feed carriage into operative position. 5

15. A sewing machine having, in combination, stitch forming devices including a needle, work supporting devices including a work support and a presser foot, a feed carriage on which the work support and presser foot are mounted, a carrier on which the feed carriage is mounted, a starting and stopping mechanism for the machine, mechanism for advancing and retracting the carriage comprising a Geneva stop motion star wheel, a cam connected to rotate therewith and arranged to actuate the carrier, and connections controlled by the starting and stopping mechanism and rendered operative upon stopping the machine to impart a predetermined angular movement to the star wheel in timed relation to the operation of the machine. 20

16. A sewing machine having, in combination, stitch forming devices including a needle, work supporting devices including a work support and a presser foot, a feed carriage on which the work support and presser foot are mounted, a carrier on which the feed carriage is mounted, a main driving shaft for the machine, a starting and 30 stopping mechanism for the machine, mechanism for advancing and retracting the carrier comprising a Geneva stop motion star wheel, a cam connected to rotate therewith and arranged to actuate the carrier, connections actuated in timed relation to the main driving shaft of the machine when rendered operative to impart a predetermined angular movement to the star wheel to advance or retract the carrier, a detent mechanism arranged normally to hold said connections 35 in inoperative position, and selective control devices actuated from the starting and stopping mechanism for actuating said trip mechanism 40 upon starting the machine only when the carrier is in its advanced position, and upon stopping the machine only when the carrier is in its 45 retracted position. 50

17. A sewing machine having, in combination, stitch forming devices including a needle, work supporting devices including a work support and a presser foot, a feed carriage on which the work support and presser foot are mounted, a starting and stopping mechanism for the machine, mechanism for advancing and retracting the carriage comprising a Geneva stop motion star wheel, 60 connections actuated when rendered operative to impart a predetermined angular movement to the star wheel to advance or retract the carriage in timed relation to the operation of the machine, and selective control devices actuated 65 from the starting and stopping mechanism for rendering said connections operative upon starting the machine only when the carrier is in its advanced position, and upon stopping the machine only when the carrier is in its retracted position. 70

18. A sewing machine having, in combination, stitch forming devices including a needle, work supporting devices including a work support and a presser foot cooperating therewith to position 75

the work in the machine, starting and stopping mechanism comprising means for driving the machine at relatively high and low speeds, mechanism rendered operative upon stopping the machine for actuating said work support and presser foot to move the work out of the path of the needle, and connections rendered operative in stopping the machine for operating the machine at low speed during said movement of the work support and presser foot.

19. A sewing machine having, in combination, stitch forming devices including a needle, work supporting devices including a work support and a presser foot, a feed carriage on which the work support and presser foot are mounted, a carrier on which the feed carriage is mounted, a starting and stopping mechanism for the machine including a variable speed clutch, mechanism arranged when rendered operative to advance or 10 retract the carrier in timed relation to the operation of the machine, and connections rendered operative in stopping the machine for operating said clutch to drive the machine at a relatively slow rate during the advancing movement of the carrier and thereafter to disconnect the clutch.

20. A sewing machine having, in combination, stitch forming devices including a needle, work supporting devices including a work support and a presser foot, a carrier arranged for forward and retracting movements to move the work support and presser foot and the work held thereby into and out of operative relationship to the needle, mechanism arranged when rendered operative to advance or retract the carrier in timed relation to the operation of the machine, and starting and stopping mechanism for the machine comprising a variable speed starting and stopping clutch, and connections rendered operative in stopping the machine for actuating the clutch to operate the machine at a relatively slow rate and simultaneously to cause the carrier to be advanced to move the work out of operative relationship to the needle, and connections actuated by said advancing movement of the carrier to disconnect the clutch.

21. A sewing machine having, in combination, stitch forming devices including a needle, work supporting devices including a work support and a presser foot, a thread cutting and holding device arranged to cut and hold the sewing thread, means rendered operative upon stopping the machine for actuating said work support and presser foot to move the work out of the path of the needle, and mechanism rendered operative by the advancing movement of the work support and presser foot for actuating said thread cutting and holding devices.

22. A sewing machine having, in combination, stitch forming devices including a hook needle, a needle threading device and a locking thread mechanism, work supporting devices including a work support and a presser foot, a thread cutting and holding device arranged to cut and hold the needle and locking threads, means rendered operative upon stopping the machine for actuating said work support and presser foot to move the work out of the path of the needle, and mechanism rendered operative by the advancing movement of the work support and presser foot for actuating said thread cutting and holding devices.

23. A sewing machine having, in combination, stitch forming devices including a hook needle, a needle threading device and a locking thread

mechanism, work supporting devices including a work support and a presser foot, a carriage on which said work support and presser foot are mounted, a thread cutting and holding device arranged to cut the needle and locking threads on one side of the work and to grip the severed ends of both threads, and means acting in timed relation to the operation of the stitch forming devices rendered operative upon stopping the machine and during the continued operation of the stitch forming devices for actuating said carriage to move the work out of the path of the needle to actuate the said thread cutting and holding devices.

24. In a sewing machine, the combination of a hook needle, a needle threading device, a shuttle located on the same side of the work with the needle, and a thread cutting device arranged to cut both the needle and the shuttle threads on the same side of the work.

25. In a sewing machine, the combination of a hook needle, a looper for placing a thread in the hook of the needle, a shuttle located on the same side of the work with the needle, and a thread cutting knife arranged to cut both the needle and shuttle threads on the shuttle side of the work.

26. In a sewing machine, the combination of stitch forming devices including a hook needle, a needle threading device, a take-up, a locking thread mechanism comprising a shuttle located on the same side of the work with the needle, and a thread cutting device located on the shuttle side of the work acting when rendered operative in timed relation to the operation of the stitch forming devices and prior to the pulling in of the loop of needle thread by the take-up in setting the stitch to cut the needle and the locking threads.

27. In a sewing machine, the combination of stitch forming devices including a hook needle, a needle threading device, a locking thread mechanism comprising a shuttle located on the same side of the work with the needle, and a thread cutting device rendered operative upon stopping the machine and acting in timed relation to the operation of the stitch forming devices to cut the needle and the locking threads on the shuttle side of the work.

28. In a sewing machine, the combination of stitch forming devices including a hook needle, a needle threading device, a locking thread mechanism comprising a shuttle located on the same side of the work with the needle, a thread cutting device arranged to cut both the needle and locking threads on the same side of the work, and thread gripping devices arranged to grip the severed ends of the needle and locking threads respectively on opposite sides of the work.

29. In a sewing machine, the combination of stitch forming devices including a hook needle, a looper for placing the needle thread in the hook of the needle, a shuttle located on the same side of the work with the needle, a thread cutting mechanism arranged to cut both the needle and shuttle threads on the shuttle side of the work, and gripping devices arranged to grip the needle and shuttle threads respectively on opposite sides of the work.

30. In a sewing machine, the combination of stitch forming devices including a hook needle, a looper, a thread take-up, a shuttle located on the same side of the work with the needle, a thread cutting device located on the shuttle side

- of the work, thread gripping devices for gripping the needle and shuttle threads respectively on opposite sides of the work, and means rendered operative on stopping the machine and 5 acting in timed relation to the operation of the stitch forming devices for actuating the thread cutting and gripping devices to cut the needle and shuttle threads prior to the drawing in of the needle loop by the take-up and to grip the 10 severed ends.
31. In a sewing machine, the combination of work feeding and stitching devices including a work support, a presser foot, a hook needle arranged to pass through an aperture in the work 15 support, a shuttle mounted together with the needle on the same side of the work as the work support, and a cutter member arranged to move with relation to the work support across the aperture to sever the needle and locking threads 20 on the same side of the work.
32. In a sewing machine, the combination of work feeding and stitching devices including a hook needle, a presser foot, a work support comprising an arcuate-shaped member provided 25 with an aperture to permit the passage of the needle and U-shaped to form a guideway on the under side of the work support, an arcuate-shaped cutter member arranged to ride in said guideway across the needle aperture to sever the 30 sewing thread, and means for actuating the cutter member to sever the sewing thread.
33. In a sewing machine, the combination of stitch forming devices including a hook needle, a needle threading device, a locking thread 35 mechanism comprising a shuttle located on the same side of the work with the needle, a work support located on the same side of the work with the shuttle, a thread cutter arranged to slide in said work support to cut both the needle and locking threads, a thread holder for positioning the severed end of the shuttle thread, and a device acting in advance of the cutter to cause the severed end of the shuttle thread to 40 be engaged by said holder.
34. In a sewing machine, the combination of 45 stitch forming devices including a hook needle, a needle threading device, a locking thread mechanism comprising a shuttle located on the same side of the work with the needle, a work support located on the same side of the work as the shuttle and provided with an aperture through which the needle is arranged to operate, a holder comprising a spring clip arranged to receive the severed end of the shuttle thread, a 50 cutter member arranged to cooperate with the under side of the work support to sever the needle and locking threads on the same side of the work, and a guide member arranged to move with the knife positioned beneath and in advance thereof to engage the severed end of the 55 shuttle thread with the holder.
35. In a sewing machine, the combination with 60 stitch forming devices, of a work support, a presser foot, presser foot supporting and actuating mechanism, including a wedge box, a wedge block mounted therein and operatively connected to the presser foot, a locking wedge block arranged to engage said presser foot wedge block between correspondingly angled surfaces 65 formed on adjacent portions of the wedge box to lock the presser foot against movement away from the work, spring means for holding the presser foot yieldingly in clamping position, the spring means tending to move the wedge block 70 into engagement with said angled surfaces to 75 lock the presser foot in clamping position, and a presser foot lifting member arranged to raise the presser foot and simultaneously to raise the wedge block out of locking position at a faster rate.
36. In a sewing machine, the combination with 80 stitch forming devices, of a work support, a presser foot, a presser foot supporting and actuating mechanism including a presser foot supporting member, a wedge box, a wedge-shaped locking member arranged to engage between correspondingly angled surfaces formed on the wedge box and on said presser foot mechanism to lock the presser foot and presser foot member against movement away from the work, spring means 85 for holding the presser foot in clamping position, spring means tending to move the wedge-shaped member into engagement with the said angled surfaces to lock the presser foot in clamping position, a presser foot lifting lever arranged to 90 engage with and raise the presser foot member, a connection from said lever at a point more remote from the pivot of the lever for raising the wedge-shaped locking member at a faster rate, and means for adjusting the operative connections 95 between the lever, and the wedge-shaped locking member and presser foot member to adjust the relative timing in the operation of said elements.
37. In a sewing machine, the combination with 100 stitch forming devices, of a work support, a presser foot member, a presser foot mounted on the member, a wedge box, a wedge-shaped member mounted for sliding movement in the wedge box and connected for movement with the presser foot member, a wedge-shaped locking member arranged to slide in the wedge box, the said parts being arranged to provide a locking engagement of said wedges in the wedge box to lock the presser foot in clamping position, and a 105 presser foot lifting lever arranged to engage with and raise the presser foot and simultaneously to raise the wedge-shaped locking member out of locking position at a faster rate.
38. In a sewing machine, the combination with 110 stitch forming devices, of a work support, a presser foot member, a presser foot mounted on the member, a wedge box, a wedge block slidably mounted in the wedge box and connected for movement with the presser foot member, a locking wedge block slidably mounted in the wedge box and cooperating with the said wedge block to lock the presser foot in clamping position, a presser foot lifting lever, a member adjustably mounted on said lifting lever to engage with and 115 raise the presser foot and member, and a link connecting the locking wedge block and the lifting lever at a point more remote than said adjustable member from the pivot of the lifting lever.
39. In a sewing machine, the combination with 120 125 stitch forming devices, of a work support, a presser foot member, a presser foot mounted on the member, a slidably mounted wedge block connected for movement with the presser foot member, a slidably mounted locking wedge block 130 cooperating with the wedge block to lock the presser foot in clamping position, spring means for holding the presser foot yieldingly in clamping position, a presser foot lifting lever arranged to engage with and raise the presser foot member to release the work, a connection connecting the locking wedge block to the lifting lever at a point more remote than the point of operative engagement of the lever with the presser foot member, spring means tending to rotate the lever 135

in a direction to bring the locking wedge block into position to lock the presser foot in clamping position, and means acting in timed relation to the operation of the machine for rotating the lever to unlock and lift the presser foot out of clamping engagement with the work.

40. In a sewing machine, the combination of feeding and stitch forming devices including a work support, a presser foot, a hook needle, a shuttle, a take-up, a supply from which thread is drawn, a thread lock located between the take-up and the supply, a carriage on which the work support and presser foot are mounted, means rendered operative upon stopping the machine to advance the carriage to move the work out of the path of the needle, and means controlled by said advancing movement of the carriage to release the thread lock.

41. In a sewing machine, the combination of feeding and stitch forming devices including a work support, a presser foot, a hook needle, a shuttle, a rotary take-up, a supply from which thread is drawn, a thread lock located between the take-up and the supply, a carriage on which the work support and presser foot are mounted, means rendered operative upon stopping the machine to advance the carriage to move the work out of the path of the needle, cam actuated means controlled from the take-up to release the thread lock at a predetermined point in the rotation of the take-up, and means controlled by said advancing movement of the carriage to release the thread lock.

42. In a sewing machine, the combination with stitch forming devices including a hook needle, of a thread positioning device comprising two members movable relatively to the thread and to each other to engage between them and position the thread, and movable relatively apart to release the thread.

43. In a sewing machine, the combination with stitch forming devices including a hook needle, of a looper, and a thread finger arranged to engage the thread between the looper and the work comprising two members movable relatively to the thread and to each other to engage between them and position the thread, and movable relatively apart to release the thread.

44. In a sewing machine, the combination with stitch forming devices including a hook needle, of a looper and a thread finger arranged to engage thread between the looper and the work comprising a pair of arms provided with offset engaging tips, means for moving the arms relatively to each other and to the thread to cause said tips to engage around and position the thread, and thereafter to release the thread.

45. In a sewing machine, the combination with stitch forming devices including a hook needle, of a looper, and a thread finger arranged to engage the thread between the looper and the work comprising a pair of arms arranged to engage between them and position the thread, a post to which one of said arms is secured, a pivot on said post about which the other of said arms is arranged to turn, a pivotally mounted track in which the post is arranged to slide, and a cam follower connection between the bracket and the rotatable arm for causing the lengthwise movement of the post to open and close the arms.

46. In a sewing machine, the combination of stitch forming devices including a hook needle, a forked looper for engaging the needle thread in the needle hook, and a thread finger comprising a pair of arms movable relatively to each other

and to the thread to engage the thread between them and to position the thread across the fork of the looper, and thereafter to release the thread.

47. In a sewing machine, the combination of stitch forming devices including a hook needle, a forked looper for engaging the needle thread in the needle hook, a thread finger comprising a pair of arms arranged to engage the thread between them, a post to which one of said arms is rigidly secured, a pivot on said post for the other of said arms, a bracket in which the post is arranged for lengthwise movement toward and away from the work, a pivotal connection for the bracket for imparting lateral movements to the arms, means for causing the lengthwise movements of the post to open and close the arms, and mechanism for controlling the operation of the post and the bracket to cause the arms to engage and position the thread across the forked end of the looper, and thereafter to release the thread.

48. A sewing machine having, in combination, stitch forming devices including a needle, clamping devices for supporting the work in the machine, and means rendered operative upon starting the machine for actuating said clamping devices to move the work into the path of the needle.

49. A sewing machine having, in combination, with supporting and stitch forming devices including a needle, a work support, a presser-foot cooperating therewith to position the work in the machine, and means rendered operative upon starting the machine for actuating said work support and presser-foot to move the work into the path of the needle.

50. A sewing machine having, in combination, work supporting and stitch forming devices including a needle, and mechanism acting upon starting the machine to move the work into the path of the needle in timed relation to the movement of the stitch forming devices.

51. A sewing machine having, in combination, stitch forming devices including a needle, work supporting devices including a work support and a presser-foot cooperating therewith to position the work in the machine, starting and stopping mechanism comprising means for driving the machine at relatively high and low speeds, mechanism rendered operative upon starting the machine for actuating said work support and presser-foot to move the work into the path of the needle, and connections rendered operative in starting the machine for operating the machine at low speed during said movement of the work support and presser-foot.

52. In a sewing machine the combination with stitch forming devices, of a work support, a presser-foot, a presser-foot bar upon which the presser-foot is mounted, parallel links supporting the presser-foot bar, and presser-foot actuating and locking mechanism including a wedge box, a wedge block mounted therein and operatively connected to the presser-foot wedge block between correspondingly angled surfaces formed on adjacent portions of the wedge box to lock the presser-foot against movement away from the work, spring means acting on the presser-foot bar to hold the presser-foot yieldingly in clamping position, and means for actuating the wedge block to lock and unlock the presser-foot.

53. In a sewing machine, the combination of feeding and stitch forming devices including a work support, a presser foot, a hook needle, a shuttle, a take-up, a supply from which thread is drawn, a thread lock located between the take-up and the supply, a carriage on which the work

support and presser-foot are mounted, means rendered operative upon stopping the machine to advance the carriage to move the work out of the path of the needle, means controlled by said advancing movement of the carriage to sever and grip the needle thread, and means acting simultaneously therewith to open the thread lock.

54. In a sewing machine, the combination of feeding and stitch forming devices including a work support, a presser foot, a hook needle, a shuttle, a take-up, a supply from which thread is drawn, a thread lock located between the take-up and the supply, a carriage on which the work support and presser foot are mounted, means rendered operative upon stopping the machine to advance the carriage to move the work out of the path of the needle, means controlled by the advancing movement of the carriage to sever a partially drawn-in needle loop beneath the work and to grip the severed end, and means acting simultaneously therewith to open the thread lock.

55. A sewing machine having, in combination, stitch forming devices including a needle and a locking thread mechanism, work supporting devices including a work support and a presser foot, means rendered operative upon stopping the machine for actuating the work support and presser-foot to move the work out of the path of the needle, a holding device for the free end of the needle thread, and means for actuating the holding device to grip the thread during the movement of the work out of the path of the needle.

56. A sewing machine having, in combination, stitch forming devices including a needle and a locking thread mechanism, work supporting devices including a work support and a presser-foot, a holding device for the needle thread mounted upon the presser-foot, means rendered operative upon stopping the machine for actuating the work support and presser-foot to move the work out of the path of the needle, and means for actuating the thread holder to grip the thread during the movement of the work out of the path of the needle.

45 57. A sewing machine having, in combination, stitch forming devices including a needle and a locking thread mechanism, work supporting devices including a work support and a presser-foot,

means rendered operative upon stopping the machine for actuating the work support and presser-foot to move the work out of the path of the needle, a holding device for the free end of the needle thread, means for actuating said holding device to grip the thread during the movement of the work out of the path of the needle, and mechanism acting after the return of the work support and presser-foot to normal work supporting position and, after the machine has been again thrown into operation, for actuating the thread holding device to release the thread.

58. A sewing machine having, in combination, stitch forming devices including a needle and locking thread mechanism, work supporting devices including a work support and a presser-foot, means rendered operative upon stopping the machine for actuating the work support and presser-foot to move the work out of the path of the needle, a holding device for the free end of the needle thread, means for actuating said device to grip the thread during the movement of the work out of the path of the needle, and mechanism acting after the return of the work support and presser-foot to work receiving position and after at least a complete cycle of operations of the stitch forming devices in beginning a new seam for actuating the holding device to release the thread.

59. A sewing machine having, in combination, stitch forming devices including a needle and a locking thread mechanism, work supporting devices including a work support and a presser-foot, means rendered operative upon stopping the machine for actuating the work support and presser-foot to move the work out of the path of the needle, a thread holding finger, a slide carrying said finger mounted on the presser-foot arranged to be actuated to grip the thread by the movement of the work support and presser-foot in moving the work out of the path of the needle, and means for actuating said slide to release the thread after the work support and presser-foot have returned to work receiving position and during the operation of the stitch forming devices in sewing a new seam.

FRED ASHWORTH.
